DESIGN FOR A TOY FIGURE

Isaac D. Gindhart, Jr., Hartford, N. J., assignor to Mary W. Gindhart, Hartford, N. J.

Application October 22, 1942, Serial No. 108,595

Term of patent 14 years

To all whom it may concern:

Be it known that I, Isaac D. Gindhart, Jr., a citizen of the United States, residing at Hartford, in the county of Burlington and State of New Jersey, have invented a new, original, and ornamental Design for a Toy Figure, of which the following is a specification, reference being had to the accompanying drawings, forming part thereof.

Fig. 1 is a side perspective view of a toy figure showing my new design.

Fig. 2 is a front view thereof.

Fig. 3 is a rear view thereof, and

Fig. 4 is a top plan view thereof.

I claim:

The ornamental design for a toy figure, as shown.

ISAAC D. GINDHART, JR.
